US00D631759S

(12) **United States Design Patent**
Diss et al.

(10) **Patent No.:** **US D631,759 S**
(45) **Date of Patent:** ** *Feb. 1, 2011

(54) **CONTAINER**

(75) Inventors: **Thomas S. Diss**, Waukesha, WI (US);
Kamchat Soisuvarn, Saugus, CA (US)

(73) Assignee: **Silgan Containers LLC**, Woodland Hills, CA (US)

(*) Notice: This patent is subject to a terminal disclaimer.

(**) Term: **14 Years**

(21) Appl. No.: **29/338,654**

(22) Filed: **Jun. 16, 2009**

Related U.S. Application Data

(63) Continuation-in-part of application No. 29/333,068, filed on Mar. 2, 2009, now Pat. No. Des. 614,049.

(51) **LOC (9) Cl.** **09-01**

(52) **U.S. Cl.** **D9/774; D9/556**

(57) **CLAIM**

We claim the ornamental design for a container, as shown and described.

DESCRIPTION

FIG. 1 is a perspective view of the claimed design;

FIG. 2 is a front view of the claimed design, the rear view, the left side view, and the right side view being the same as the front view;

FIG. 3 is a top view of the claimed design; and,

FIG. 4 is a bottom view of the claimed design.

The ornamental design which is claimed is shown in solid lines in the drawings. The broken lines in the drawings are for illustrative purposes only and form no part of the claimed design.

1 Claim, 3 Drawing Sheets
